ILLINOIS, ASSIGNEES TO H. A. BRASSERT & COMPANY, OF CHICAGO, ILLINOIS, A
CORPORATION OF ILLINOIS

FURNACE

Application filed October 9, 1929. Serial No. 398,302.

This invention relates to a new and improved furnace of the vertical shaft type, and more particularly to an improvement in the upper portion of furnaces of this character especially adapted for use as blast furnaces for the production of pig iron.

During the past twenty years the trend of blast furnace design has been more and more to increase the diameter of the hearth of the furnace and at the same time to steepen the bosh angle and lower the height of the bosh. The result has been that blast furnaces today are much larger at the bottom than at the top. It will readily be seen that when the optimum wind is blown to correspond to this greater increase in hearth area, that the velocity of the gases at the top of the furnace is very great, and in some cases twice of what it used to be when the furnace hearth was not materially larger than the top area, and consequently only a half of the wind volume blown.

The difficulty in regard to increasing the top dimensions to correspond with the increased hearth dimensions has been that it is not possible to obtain good distribution when discharging the raw materials from a large bell into the furnace, unless the distance between the large bell and the furnace wall is kept within comparatively narrow limits. It is also not desirable to use too large a bell because with a larger bell the depression of the stock below the bell becomes too pronounced, resulting in the coarse materials rolling into this depression and causing irregularity in the distribution of coarse and fines, and in turn a very porous column in the center of the shaft.

We propose to overcome these difficulties by flaring out the lines of the blast furnace at the top. In this way we are able to maintain the most desirable batter of the furnace inwall, which is required in order to have a free working furnace and yet to have a stock line area of such proportions that the velocity of the gases at the top is very considerably reduced. We have ascertained that within the layers of material nearest to the top, called stock line, the pressure drop per vertical foot of stock drops faster than in the sections below, indicating a greater resistance to gas flow

in the uppermost area. By widening out the top section this resistance is decreased and the speed of the flow of the gases is reduced. Furthermore, with this design a larger size bell can be used without detriment, as the inverted batter will cause the materials to close in toward the center, thereby tending to fill up the depression under the big bell. This rearrangement of materials will cause a cross mixing of the materials deposited next to the wall with those which will have rolled into the center.

A further advantage of the reduced speed of the gases near the top of the furnace is that less flue dust will be produced in this section and that flue dust which has been generated in lower sections will tend to deposit in the upper section, thereby greatly reducing the amount of flue dust produced. The cross mixing of the stock will afford a better contact between the gases and the solids, and will result in a saving of fuel, the advantage of which is self-evident. The importance of reducing flue dust losses is equally evident and is a matter of increasing importance with the higher rate of driving and production on the one hand, and the increased cost of ore on the other.

A further advantage of our invention lies in the fact that it permits us to design a furnace of a lesser height for equal production. The preheating of the burden, the calcining of the flux, and the reduction of the ores primarily takes time. The necessary time element can be secured either by building the furnace higher or by making it wider. In both cases the length of time of contact between gases and solids is increased. If this is done by increased height, the blast pressure is increased, resulting in a great expenditure for power in blowing and more costly construction of the furnace and wastage of energy in hoisting the materials to the top. Furthermore, with an increased velocity of gases through the furnace by means of an increased height of the descent of the charges the abrasion within the furnace is increased. The coke is partially destroyed by a reduction of size before it reaches the

hearth, resulting in the well known difficulties of operation.

With our type of furnace the same factor of time is secured with a decrease in pressure, a decrease in height of stock column, with a decreased tendency of channeling which is generally caused by too high a velocity in certain sections of the column.

Another advantage we claim for our invention is that the inverted batter in the top will protect the stock line due to the fact that the stock will lie close to the wall, the fines protecting the lining against abrasion and the stock line armament, which generally consists of cast iron or steel members embedded in the brick work, will not be so apt to fall out due to undercutting of the brick work. Furthermore, with our design of furnace the high temperature gases will not tend to flow up along the walls, an occurrence which is frequent in usual furnace practice and always results in the rapid destruction of the lining.

Another feature of our invention relates to the provision of means for anchoring and protecting the upper portion of the brick lining of the furnace. The linings of furnaces of this character expand and contract under variation in heat conditions and the vertical movement of the lining in furnaces of the present commercial sizes is considerable in extent. According to our invention we provide means for slidably connecting this upper portion of the brick work to the metal shell so that stresses occurring in both the brick work and shell are minimized and the brick work is held in place against the shell.

We have also provided a construction wherein the brick work in the uppermost portion of the furnace may be supported by the shell independently of the brick work in the main body of the furnace. This uppermost brick work is thereby not affected by any vertical movement of the main brick work.

It is an object of the present invention to provide a new and improved vertical shaft furnace and more particularly to provide a new and improved upper construction for such a furnace.

It is an additional object to provide a furnace wherein the quantity of flue dust produced and carried off from the furnace is reduced and wherein the gas velocities in the uppermost portion of the furnace are reduced.

It is a further object to provide a construction in which the materials charged to the furnace are more uniformly distributed throughout the furnace area than in customary furnace construction, and in which a better distribution is had of the ascending gases among the descending materials.

It is also an object to provide a construc-

tion of furnace lining whereby the lining is slidably connected to the shell.

It is an additional object to provide a construction in which stock line protection plates are slidably connected to the shell.

It is also an object to provide a construction in which the brick work in the uppermost portion of the furnace is supported by the shell independently of the lower brick work.

Other and further objects will appear as the description proceeds.

We have illustrated certain preferred embodiments of our invention in the accompanying drawings, in which—

Figures 1, 2 and 3 are somewhat diagrammatic showings of different forms of furnaces;

Figure 4 is a section on an enlarged scale of the upper portion of the furnace constructed according to our invention;

Figure 5 is a fragmentary section taken on line 5—5 of Figure 4 and shown on an enlarged scale; and

Figure 6 is a fragmentary vertical section of part of Figure 4 on an enlarged scale.

Referring first to the forms of construction shown in Figures 1, 2 and 3, in Figure 1 a furnace is outlined having a hearth portion 11, an outwardly flaring bosh portion 12, an inwardly inclined frusto-conical shaft portion 13, and an outwardly flaring uppermost portion 14. The portion 14 is shown as rounded and the junction at 15 between the portions 13 and 14 is also rounded. The charging bell is shown at 16.

In Figure 2 a furnace is shown having a hearth portion 17, a flaring bosh portion 18, and a substantially cylindrical shaft portion 19. The uppermost portion 20 inclines outwardly and is in the form of an inverted frustum of a cone. The portion 20 joins the portion 19 on line 21. The charging bell is shown at 22.

The form of construction shown in Figure 3 is generally similar to that shown in Figure 1 and comprises a cylindrical hearth portion 23, flaring bosh portion 24, inwardly inclined shaft portion 25 formed as the frustum of a cone, and a topmost portion 26 formed as an inverted frustum of a cone and meeting the portion 25 on line 27. The charging bell is shown at 28.

In Figure 4 we have shown more in detail a form of construction similar to that shown in Figure 1. Here the metal furnace shell 29 is provided with a brick lining 30 and with the stock line protecting plates 31. These plates 31 are located at the line of junction between the shaft portion of the furnace and the outwardly flaring portion 32, and are tied into the shell 29 by connecting plates 33. The offtake passages 34 serve to carry the products of combustion and blast gases to the downcomers. The lower charging bell 35

may be operated by any usual bell operating mechanism and is shown as engaging the lower hopper section 36.

The details of construction of the brick work and stock line protection plates are shown in Figures 5 and 6. The brick lining 30 is shown as provided with a series of plates 37 which have upwardly extending portions 38 bonding them into the brick work. Above 10 this point are the plates 39 having upwardly extending portions 40 bonding them to the brick work and having the T-shaped heads 41 which protect the faces of the brick work immediately below the stock line protection 15 plates 31. These plates 31 have extensions 42 which are located behind the T-heads 41 of the plates 39 and serve to hold the lower edges of the plates 31 in place.

The upper edges of the plates 31 have inwardly extending portions 43 and vertically extending portions 44, these latter engaging back of the vertically extending portions 45 of the connecting plates 33. As best shown in the horizontal section of Figure 3, the connecting plates 33 are provided with the extensions 46 which engage behind the T-heads 47 of the rails or tracks 48. These rails or tracks 48 are secured to the inner surface of the metal shell 29.

It will be noted that the upper portion 49 of the metallic shell 29 extends upwardly inside the furnace, the upper portion of which is enclosed by the upwardly flaring shell section 50. The topmost portion 51 of the main 35 brick work in the furnace is located inside of the shell extension 49. The brick work 32 in the uppermost portion of the furnace is thus supported by the plates 49 and 50 independently of the main body of the brick work 40 in the furnace. Therefore any vertical expansion or contraction of the main brick work will not affect the uppermost brick work 32. It will also be apparent that due to the 45 sliding connection between the plates 33 and the T-shaped rails 48 substantially no stresses are set up in the shell and there is no rupturing of the brick work when the brick work moves under expansion and contraction.

There are no holes or openings in the brick 50 work necessary, as is the case where usual types of tie rods or bars are used to hold the brick lining back against the metal shell. The stock line protection plates are effectively tied into the brick work and will not be 55 come loosened and fall out upon the impact of the incoming material. It will be apparent from a consideration of Figure 4 that the incoming material will strike the inwardly sloping surfaces of the upper portion of 60 the furnace and will be directed inwardly toward the center of the furnace. This will serve to reduce the usual depression below the bell and will more uniformly mix the various sizes of material throughout the cross 65 sectional area of the furnace.

While we have shown certain preferred embodiments of our invention by way of example, it is capable of change and modification to meet varying conditions and requirements, and we contemplate such variations 70 and changes as come within the spirit and scope of the appended claims.

We claim:

1. In a vertical shaft furnace, an intermediate portion and an upper portion, brick 75 work lining the intermediate section and brick work lining the upper portion, the brick work of the upper portion being supported independently of the brick work in the intermediate portion.

2. In a vertical shaft furnace, a metallic shell, an intermediate portion and an upper portion, brick work lining the intermediate section and brick work lining the upper portion 85 being supported by the shell independently of the brick work in the intermediate portion.

3. In a vertical shaft furnace, a metal shell, a brick lining for the shell, and means connecting the shell and lining, said means having a sliding connection with the shell.

4. In a vertical shaft furnace, a metal shell, a brick lining for the shell, and means connecting the shell and lining, said means comprising vertically extending T-shaped members secured to the shell and members carried by the brick work and slidably engaging the T-shaped members.

5. In a blast furnace, a metal shell, a brick lining, an upper outwardly flared portion 100 of the brick lining located at the stock line, and means slidably connecting the brick work to the shell at the stock line.

6. In a blast furnace, a metal shell, a brick lining, an upper outwardly flared portion of 105 the brick lining located at the stock line, and means slidably connecting the brick work to the shell at the stock line, said means including stock line protection plates on the inner surface of the brick and means slidably connecting said plate to the shell.

7. In a blast furnace, a metal shell, a brick lining, metal stock line plates fitted upon 115 said brick lining, and means slidably connecting said plates to the shell.

8. In a blast furnace, a metal shell, a brick lining, metal stock line plates fitted upon said brick lining, and means slidably connecting the plates to the shell, said means including vertically extending track members and 120 members extending through the lining connected to the plates and slidably engaging the tracks.

9. In a blast furnace, a metal shell, a brick lining, stock line plates fitted in the brick 125 lining at the stock line, said plates having inwardly and vertically extending portions, connecting plates having vertically extending portions engaging the vertically extending portions of the stock line plates, and 130

- means slidably connecting the connecting plates to the shell.
10. In a blast furnace, a metal shell, a brick lining, stock line plates fitted in the brick lining at the stock line, said plates having inwardly and vertically extending portions, connecting plates having vertically extending portions engaging the vertically extending portions of the stock line plates, vertically extending T-shaped tracks secured to the inner surface of the shell, and portions formed on the connecting plates extending behind the heads of the T-shaped tracks to slidably connect the connecting plates and stock line plates to the shell.
11. In a blast furnace, a furnace shaft having an upper portion extending below and above the stock line and flaring outwardly whereby the upper portion of the stock has 20 a greater gas releasing area than a lower portion of the stock whereby gas velocity is reduced at the upper stock surface and gas off-takes in communication with the entire upper surface of the stock.
12. In a blast furnace, a furnace shaft having walls sloping upwardly and inwardly and an upper wall portion flaring upwardly and outwardly, the junction of the two portions being located below the stock line, a curved 20 portion at the junction whereby the interior of the upper portion of the furnace is of generally Venturi section and gas off-takes in communication with the entire upper surface of the stock.
13. In a blast furnace, a shaft having walls sloping inwardly and upwardly and an upper section sloping outwardly and upwardly, the plane of junction of the oppositely sloping walls containing a lesser furnace interior 30 cross section than planes thereabove, said plane of junction being located below the stock line, and a bell carried by the furnace top at a point materially above the plane of minimum furnace area and sloped to discharge material directly against the upper outwardly flaring walls whereby the material is directed by said walls inwardly and downwardly to reduce the stock depression below the bell.
14. In a blast furnace, a shaft having walls sloping inwardly and upwardly and an upper section sloping outwardly and upwardly, the plane of junction of the oppositely sloping walls containing a lesser furnace interior 40 cross section than planes thereabove, said plane of junction being located below the stock line, a bell carried by the furnace top at a point materially above the plane of minimum furnace area and sloped to discharge 45 material directly against the upper outwardly flaring walls whereby the material is directed by said walls inwardly and downwardly to reduce the stock depression below the bell and gas off-takes connected to the upper portion of the furnace and communi-
- cating with the space above the entire upper stock surface.
15. In a blast furnace, a shaft having walls sloping inwardly and upwardly and an upper section sloping outwardly and upwardly, 70 the plane of junction of the oppositely sloping walls containing a lesser furnace interior cross section than planes thereabove, said plane of junction being located below the stock line, and a bell carried by the furnace top at such a height above the stock line and so sloped as to discharge material directly against the upper outwardly flaring walls which causes the materials to lie closely against the wall thereby forcing gases away 75 from the walls.
